US00D919635S

(12) **United States Design Patent** (10) **Patent No.:** **US D919,635 S**
Chiu et al. (45) **Date of Patent:** **** May 18, 2021**

(54) **DISPLAY SCREEN OR PORTION THEREOF WITH GRAPHICAL USER INTERFACE**

(71) Applicant: **CyCraft Singapore Pte. Ltd.**,
Singapore (SG)

(72) Inventors: **Ming-Chang Chiu**, New Taipei (TW);
Sheng-Yang Peng, New Taipei (TW);
Pei Kan Tsung, Taoyuan (TW); **Ming Wei Wu**, New Taipei (TW)

(73) Assignee: **CyCraft Singapore Pte. Ltd.**,
Singapore (SG)

(**) Term: **15 Years**

(21) Appl. No.: **29/697,650**

(22) Filed: **Jul. 10, 2019**

(51) LOC (13) Cl. **14-04**

(52) U.S. Cl.

USPC **D14/485**

(58) **Field of Classification Search**

USPC **D14/485-495**

CPC **G06F 3/048-04897**

See application file for complete search history.

(57) **CLAIM**

The ornamental design for a display screen or portion thereof with graphical user interface, substantially as shown and described.

DESCRIPTION

The FIGURE is a front view of a display screen or portion thereof with graphical user interface showing the claimed design.

The broken lines, texts, and numerals in the figures show portions of the graphical user interface that form no part of the claimed design.

The outmost dot-dashed lines in the figures show a display screen or portion thereof, and form no part of the claimed design.

1 Claim, 1 Drawing Sheet
